(57) **CLAIM**

The ornamental design for a core color display module, as shown and described.

DESCRIPTION

FIG. 1 is a perspective view;

FIG. 2 is an alternate perspective view; with portions cut away to reveal underlying details more clearly;

FIG. 3 is a front elevational view;

FIG. 4 is a cross-sectional view taken along line 4-4 of FIG. 3;

FIG. 5 is a cross-sectional view taken along line 5-5 of FIG. 3; and

FIG. 6 is an enlarged detail view taken from the detail enlargement portion labeled "6" in FIG. 1;

FIG. 7 is an enlarged detail view taken from the detail enlargement portion labeled "7" in FIG. 2;

FIG. 8 is an enlarged detail view taken from the detail enlargement portion labeled "8" in FIG. 3;

FIG. 9 is an enlarged detail view taken from the detail enlargement portion labeled "9" in FIG. 4; and,

FIG. 10 is an enlarged detail view taken from the detail enlargement portion labeled "10" in FIG. 5.

The dash-dash broken lines are shown for the purpose of illustrating portions of the core color display module that form no part of the claimed design. The dot-dash broken lines are employed to isolate and identify enlargement portions of the design. The dot-dot-dash broken lines shown on FIG. 2 are for the purpose of showing portions cut away to show underlying details more clearly and form no part of the claimed design.
